UNITED STATES PATENT OFFICE.

JAMES M. BASINGER, OF BUFFALO, NEW YORK, ASSIGNOR OF ONE-FOURTH
TO PRATT & LETCHWORTH, OF SAME PLACE.

HAME-TUG.

SPECIFICATION forming part of Letters Patent No. 288,759, dated November 20, 1883.

Application filed September 28, 1883. (No model.)

To all whom it may concern:

Be it known that I, JAMES M. BASINGER, of the city of Buffalo, in the county of Erie and State of New York, have invented a new 5 and useful Improvement in Hame-Tugs, of which the following is a specification.

This invention relates to a loop arranged near the front end of the hame-tug for the reception of the front end of a long trace, 10 which projects forwardly beyond the loops ordinarily secured to the body of the hame-tug.

The object of my invention is to secure this loop to the hame-tug in a strong and durable manner; and my invention consists of the improvement in the construction of the hame-tug, which will be hereinafter fully set forth, 15 and pointed out in the claims.

In the accompanying drawings, Figure 1 represents a longitudinal horizontal section of 20 a hame-tug provided with my improvement. Fig. 2 is a vertical cross-section in line $x x$, Fig. 1. Fig. 3 is a perspective view of the loop. Fig. 4 is a perspective view, showing a modified construction of the loop.

25 Like letters of reference refer to like parts in the several figures.

A represents the hame-tug, and B the front portion of the trace.

C represents the hame-clip, having its legs 30 c inserted between the several thicknesses of leather of which the hame-tug is composed.

D represents the loop adapted to receive the front end of the trace, and secured to the front end of the tug on the outer side of the same.

35 d is the stud or rivet whereby the loop is secured to the tug. This rivet passes through the legs of the hame-clip and serves at the same time to secure the clip to the tug, while the legs of the clip in turn form a rigid support 40 for the rivet and enable the latter to hold

the loop securely in position on the tug. As shown in Figs. 1, 2, and 3, the stud d is cast directly on the loop; but, if preferred, the loop may be provided with a perforated ear, e , as represented in Fig. 4, and be secured to 45 the tug by an ordinary rivet. The base or rear side, f , of the loop is preferably made concave, to fit closely against the convex outer side of the tug, as represented in Fig. 2, and the base f is preferably provided with spurs 50 g , which embed themselves into the leather and prevent the loop from turning on its rivet, if the latter should become loose.

The loop D may be readily secured to harness already constructed upon removing one 55 of the rivets, whereby the hame-clip is secured to the tug.

My improved loop may also be applied to the breast-collars of light harness to hold the front end of a long trace. 60

I claim as my invention—

1. The combination, with a tug and hame-clip, of a loop and a stud or rivet passing through the eyes of the hame-clip and the tug, whereby the loop is secured to the tug, substantially as set forth. 65

2. The combination, with a tug and hame-clip, of a loop cast with a stud or rivet, and spurs projecting from the base of the loop, said stud or rivet passing through the legs of 70 the clip, substantially as set forth.

3. In a hame-tug, a loop cast with a stud or rivet, and spurs projecting from its base, substantially as set forth.

Witness my hand this 24th day of September, 1883. 75

JAMES M. BASINGER.
